(57) **CLAIM**

(22) Filed: **Mar. 5, 2007**

The ornamental design for a mount for a navigation device, as shown and described.

(51) **LOC (8) Cl.** **10-04**

DESCRIPTION

(52) **U.S. Cl.** **D10/74**

FIG. 1 is an isometric view of a mount for a navigation device according to the present invention;

(58) **Field of Classification Search** 340/995;

FIG. 2 is a top plan view thereof;

364/200, 434, 443, 444, 449, 451, 708.1,

FIG. 3 is a front elevational view thereof;

364/709.11, 499; 73/178 R; 248/DIG. 4,

FIG. 4 is a side elevational view thereof;

248/121, 160, 229, 284, 291, 291.1–229.26,

FIG. 5 is a rear elevational view thereof; and,

248/689–690; D10/74; D14/347; 342/351,

FIG. 6 is a bottom plan view thereof.

342/419, 457, 357.06–357.13; 343/702;

345/87, 104, 133, 156, 168, 173, 901–905;

348/180, 184, 315, 739; 701/206–209, 213,

701/214
